UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING MACHINE.

Application filed April 19, 1924. Serial No. 707,651.

To all whom it may concern:

Be it known that I, JOSEPH S. DUNCAN, a citizen of the United States, residing at Chicago, in the county of Cook and State 5 of Illinois, have invented certain new and useful Improvements in Printing Machines, of which the following is a specification.

This invention relates to printing machines and is particularly designed for use 10 in a machine of the type disclosed in my Patent No. 1,481,860, January 29, 1924. In that patent there is shown a machine for printing addresses in duplicate, triplicate, or other predetermined number of times.

15 In such a case, as for example in printing electric light and gas bills where usually the same address is printed on different parts of the bill, it is sometimes found necessary to print different addresses on different 20 parts of the bill instead of duplicate addresses.

It is therefore the object of my invention to provide a printing machine of the general type disclosed in my aforesaid patent, 25 which will permit printing of the same address a selected number of times, or which will print different addresses on the same bill or the like, the operation of the mechanism being controlled by means on the 30 printing devices or plates.

Other objects will be in part apparent and in part pointed out during the process of the description.

Referring to the drawings forming a part 35 of this specification,

Fig. 1 is a plan view of my machine.

Fig. 2 is a sectional view taken on the line 2—2 of Fig. 1.

Fig. 3 is a section taken on the line 3—3 40 of Fig. 2.

Fig. 4 is a view similar to that of Fig. 3, showing the parts in different positions.

Fig. 5 is an elevation of a portion of my machine looking from the left of Fig. 1.

Fig. 6 is a view similar to Fig. 5, showing the parts in a different position, and

Fig. 7 is a view showing some of the parts of Figs. 5 and 6 in still another position.

Power is applied to my machine through 50 pulley 1 which, by the selective gearing 2, operates the paper feeding mechanism enclosed at 3. This feeding mechanism forms

no part of my present invention and will not be further described. The selective gearing 2 may be of any desired ratio, as 55 1:1, 2:1 or 3:1, as described in my aforesaid patent. Through beveled gearing 4 is driven shaft 5 and through other beveled gearing 6 is driven shaft 7. The shaft 5 is driven in this embodiment at the ratio 60 of 1:1, and the shaft 7 will, of course, be driven at a ratio depending upon the ratio of the selective gearing 2. In this embodiment this ratio is 2:1 giving the shaft 7 two rotations to one for the shaft 5. Obviously, 65 any other ratio which is desired may be provided.

Secured on the shaft 5 are cams 8 operating rollers 9 which bear on said cams on opposite sides of the shaft 5 and are mounted 70 on the arm 10 pivoted at 11 on the frame of the machine. The arm 10 is connected by link 12 to arm 13 on rocker 14 pivoted on bearing 15. The rocker 14 carries arms 16 to operate the inking device 17. In Fig. 3 75 said device is shown in the position wherein ink from the source 18 is being applied to pads 19, and in Fig. 4 the rocker is shown in the position wherein the pads 19 are applying ink to the printing devices or plates 20. 80 The plates 20 are fed from magazine 21 under inking device 19 and to platen 22 where impression is made therefrom on the paper fed at right angles to the course of travel of the plates by means of the paper feeding 85 mechanism, a portion of which is shown at 23. The means for feeding the plates comprise chains 24 passing over sprockets 25 at one end of the machine and sprockets 26 at the other end thereof.

Referring particularly to Figs. 5, 6 and 7, motion is imparted to chain 24 by an intermittent rotation of sprockets 26 provided by engagement of pawl 27 with pins 28 spaced circumferentially of the sprocket 26. The 90 pawl 27 is pivotally mounted on the member 29 fast on rocker 14.

In the operation of the mechanism thus far described, each rotation of shaft 5 will 95 result in one oscillation of rocker 14, as will be evident, this oscillation resulting in movement of the inking device from the position shown in Fig. 3 to that shown in Fig. 4, and back to that shown in Fig. 3. The shaft

7 is being rotated at one revolution for every two revolutions of shaft 5. Said shaft has mounted thereon cam 30 against which bears roller 31 mounted on lever 32 pivoted at 33. The other end of said lever 32 is forked, as shown at 34, to embrace pin 35 on the end of lever 36 pivoted at 37. The other end of lever 36 is pivoted to link 38 which in turn is pivoted to bell crank 10 lever 39, one end of which forms a cam 40. The roller 31 is urged into engagement with the periphery of cam 30 by means of spring 41. When in the position shown in Fig. 5, feed of the sprocket 26 by pawl 27 is 15 prevented by means of the pin 42 on said pawl riding over the surface of cam 40. During continued rotation of said shaft 7, however, the roller 31 will drop into the depression 43 of the cam 30 and through 20 the mechanism just described the cam 40 will be swung counter clock-wise, as appearing in Figs. 5 and 6, so that the pawl 27 will engage pins 28. Locking pawl 44 is provided to normally hold sprocket 26 25 against rotation and this pawl is released by the end of the cam 40, striking it when it moves to the position shown in Fig. 6. The cam 30 in the present instance is designed so as to render the plate feeding 30 mechanism inoperative while two impressions are made by the platen 22 from one plate, the platen 22 being shown in Fig. 5 in a position wherein a bill or the like is about to be fed into position at 45, after which the platen will be brought into contact therewith, as shown in Fig. 6, by means of cam 46 acting on roller 47. The member 48 is shown raised in Fig. 5 to permit movement of a plate into position, which movement has just taken place when the said member 48 is lowered to position shown in Fig. 6.

The mechanism so far described is substantially the same as that described in my aforesaid Patent No. 1,481,860, in which it was explained that the cam 30 and other mechanisms may be designed to permit the taking of any number of impressions from the one plate. In Figs. 5 and 6, the mechanism is shown in the positions that it normally takes when printing two impressions from one plate. I have provided means whereby the cam 30 will be rendered inoperative and the roller 31 will be brought to bear directly on the shaft 7 so as to permit another plate to be fed into position after one impression has been taken by platen 22 so that different addresses and the like may be printed in place of duplicate addresses. It will be noted that the bottom of the recess 43 on cam 30 is tangent with the circumference of the shaft 7 and I have provided means for moving the roller 31 axially of the shaft 7 when it reaches this depression whereby it will take the position

shown in Fig. 7 and thus maintain the feeding means in the operative position shown in Fig. 6.

Referring now particularly to Figs. 2, 3 and 4, pivoted at 49 on a fixed part of the machine is a rocking member 50 normally held in the position shown in Fig. 3 by spring 51. Pivotedly mounted on said rocker 50 at 52 is a lever 53 carrying at one end a link 54 pivoted to latch 55 controlling member 56, which in turn is carried on rock shaft 57. Member 56 and rock shaft 57 are normally urged toward the position shown in Fig. 4 by means of spring 58 but are locked in position shown in Fig. 3 by the latch member. The right hand end of the lever 53, as appearing in Figs. 3 and 4, carries a support 59 for a plurality of pins 60. The use of these pins is disclosed in my aforesaid patent and it is only necessary to note here that if one of the plates 20 is provided with a tab 61 one of the pins 60 will come in contact therewith upon depression of the support 59, as will be presently described. Carried on the inking device 17 is a pin 62 which, when in the position of Fig. 4, strikes the headed member 63 carried by the rocker 50, thus depressing the rocker and the pivot 52 of the lever 53.

It will now be evident that if the plate in position under the support 59 has no tab thereon, the pins 60 will enter the depression 64 provided for their reception, the lever 53 will be rocked about its pivot 52 by spring 53' and thus the latch 55 will be 100 maintained in the position shown in Fig. 3. If, however, a plate carrying a tab 61 is in place under the support 59, the support can not be lowered, and as the pivot 52 is lowered with the rocker 50, the left end of lever 53 will also be lowered, thus releasing the latch 55 and permitting rotation of the rock shaft 57 to the position shown in Fig. 4. Carried on the right end of said shaft 57, as viewed in Fig. 2, is an arm 65 (see also Figs. 5, 6 and 7) which arm 65 is normally held in the positions shown in Figs. 5 and 6. On the end of arm 65 is pivoted a link 66 carrying at its lower end a lever 67 pivoted to the frame of the machine at 68. It will be plain now that upon rocking of the shaft 57 the arm 65 will be carried with it to the position shown in Fig. 7. The lever 67 in its movement to the position shown in Fig. 7 and in dotted lines in Fig. 2 will come to rest against the surface 69 of cam 70 and will be forced by said cam surface against the end of shaft 71 carrying roller 31. The lever 67 is loosely pivoted and held on its pivot by spring 72, as shown in Fig. 2, 110 permitting this lengthwise movement. Shaft 71 and cam 31 fast thereon are normally held in the position shown in Fig. 2 by means of plate 73 bearing against the collar 74 on said shaft and tensioned by 115 120 125 130

- spring 75. Longitudinal movement of shaft 71 results in the roller 31, which at this point is in the depression 43 of cam 30, sliding along the shaft 7 out of contact with said cam. It will be held against the side of the cam 30 during one revolution thereof but upon return to the depression 43 will be returned to its position in contact with the edge of the cam by means of spring 75.
- 10 The left end of the rock shaft 57, as viewed in Fig. 2, is provided with a roller 76 contacting with stop 77.
- The operation of the machine has been fully brought out in the progress of the 15 description and it is not believed necessary to repeat it here in detail. It may be briefly summarized, however, as follows:—
- The paper is fed by means of the feeding mechanism, indicated generally at 3 and 23, 20 to position under the platen 22 in such a manner as to be held in position under the platen while an impression or impressions are being taken. Printing devices or plates are fed from the magazine 21 in a direction 25 at right angles to the direction in which the paper is fed and a device is brought into position under the platen and paper after it has been inked by the inking device shown in Figs. 3 and 4, and remains in said position 30 while a plurality of impressions are normally made therefrom. It is understood that the paper is given a feeding movement between said impressions. When it is desired to make only one impression from each plate 35 or device, that plate is furnished with a tab 61 which actuates the latch member 55 to permit rocking of rock shaft 57, which in turn disengages the roller 31 from the cam 30 during one revolution of the said cam 40 and the shaft 7 on which it is mounted. After this one revolution the spring 75 causes return of the roller 31 to position on the periphery of the cam 30.
- I am aware that changes in the form, 45 construction and arrangement of parts may be made without departing from the spirit and without sacrificing the advantages of the invention and I reserve the right to make all such changes as fairly fall within the scope 50 of the following claims:—
- I claim:—
1. In a printing machine, a printing device, means to take a plurality of impressions therefrom, and means to alter said first named means in order to take a single impression, said altering means being controlled by said printing device.
  2. In a printing machine, means to feed a printing device into printing position, means to take a plurality of impressions therefrom while in said position, and means controlled by said printing device to alter said feed to permit a single impression from said printing device.
  3. In a printing machine, means to feed a printing device into printing position, means to take a plurality of impressions therefrom while in said position, and means controlled by said printing device to permit a single impression from said printing device.
  4. In a printing machine, means for feeding printing devices successively into printing position, means rendering said feeding means inoperative for a period of time, and means to alter the number of feeding operations taking place between said inoperative periods, said altering means being controlled by said printing devices.
  5. In a printing machine, means for operating a platen, means for feeding printing devices to position under said platen, means for taking one or a plurality of impressions from said printing device by said platen selectively, the selection being made by said printing device.
  6. In a printing machine, means for feeding a printing device to position under a platen, means for inking said printing device before coming to said position, and means operated by said inking means to alter said printing device feed.
  7. In a printing machine, means for feeding a printing device to position under a platen, means for inking said printing device before coming to said position, and means operated by said inking means to alter said printing device feed, said altering means being controlled by said printing device.
  8. In a printing machine, means for feeding a printing device into printing position, means for rendering said feeding means inoperative, a cam to control said last named means, and means controlled by said printing device for rendering said cam means inoperative.
  9. In a printing machine, means for feeding a printing device into printing position, a platen for taking an impression from said printing device, an inking device for inking said device, means to alter said feeding means operated by said inking device and controlled by said printing device.
  10. In a printing machine, means for feeding a printing device, means for rendering said feeding means inoperative for a predetermined interval, said last named means comprising a cam and a roller contacting with the periphery of said cam, means for varying the period of time during which said feeding means is operated comprising means for moving said roller axially of said cam and out of engagement therewith.
  11. In a printing machine, means for feeding the printing device into printing position comprising a sprocket wheel, a plurality of pins circumferentially mounted on said sprocket wheel, a pawl adapted to engage said pins, and means to move said pawl into and out of engagement with said pins.

gage successively with said pins, and means for holding said pawl out of engagement with said pins to render said feeding means inoperative.

5 12. In a printing machine, means for feeding the printing device into printing position comprising a sprocket wheel, a plurality of pins circumferentially mounted on said

sprocket wheel, a pawl adapted to engage successively with said pins, and means for holding said pawl out of engagement with said pins to render said feeding means inoperative, said last named means being controlled by said printing device. 10

JOSEPH S. DUNCAN.
